RIVETING MACHINE

Edward Turnquist, Anderson, Ind., assignor to
General Motors Corporation, Detroit, Mich., a
corporation of Delaware

Application July 22, 1935, Serial No. 32,515

5 Claims. (Cl. 78—48)

This invention relates to riveting machines and more particularly to an automatic riveting machine.

It is an object of the present invention to provide for delivery of an orderly disposed rivet from a supply to a place adjacent its application.

It is another object of the present invention to place a delivered rivet without fail in the receiving apertures of properly located, overlapping work portions.

It is another object of the present invention to provide a machine which rapidly and automatically accomplishes the aforementioned objects in addition to the actual heading of a placed rivet shank upon a simple manipulation of a machine element by an operator.

Further objects and advantages of the present invention will be apparent from the following description, reference being had to the accompanying drawings wherein a preferred embodiment of the present invention is clearly shown.

In the drawings:

Fig. 1 is a fragmentary front elevation of a riveting machine embodying the present invention.

Fig. 2 is a fragmentary side elevation of the machine as viewed in the direction of arrow 2 in Fig. 1.

Fig. 3 is a sectional view of a rivet holding hopper and its mounting on the machine. This section is taken on the lines 3—3 of Figs. 1 and 4.

Fig. 4 is a fragmentary section taken substantially on the line 4—4 of Fig. 3.

Fig. 5 is a fragmentary section taken substantially on the line 5—5 of Fig. 4.

Fig. 6 is a section taken on the line 6—6 of Fig. 4.

Fig. 7 is a fragmentary section taken substantially on the line 7—7 of Fig. 4.

Fig. 8 is an enlarged fragmentary view of part of Fig. 1.

Fig. 9 is a fragmentary view similar to Fig. 8, showing certain elements of the machine in a different position of operation, however.

Fig. 10 is a fragmentary view similar to Fig. 9, showing certain machine elements in still another position of operation.

Fig. 11 is a section taken on the line 11—11 of Fig. 8.

Fig. 12 is an enlarged fragmentary view of part of Fig. 2, part thereof being shown in sec-

tion which is taken substantially on the line 12—12 of Fig. 1.

Fig. 13 is a front elevation of part of Fig. 12 as viewed in the direction of arrow 13 of Fig. 12.

Fig. 14 is a section taken substantially on the line 14—14 of Fig. 12.

Fig. 15 is a fragmentary perspective view of certain details of the machine.

Figs. 16 to 19 inclusive are sectional views similar to Fig. 12, each showing a different position 10 of operation of certain elements of the machine, however.

Fig. 20 is a front elevation of part of Fig. 19 as viewed in the direction of arrow 20 in Fig. 19.

The present machine is adapted to rivet a 15 mounting bracket to an automobile lamp housing, but it is to be understood that this machine is capable of a much more universal application and accordingly may, for instance, be adapted to rivet two or more over-lapping portions of 20 any type of work together. Briefly, the operator of the machine brings the rivet receiving holes of over-lapping work portions into registry with a yielding pilot pin of the machine. Thereafter the operator starts the machine for one cycle of 25 operation by a simple manipulation of a machine element, resulting in delivery of a rivet from a store to a place adjacent its application, setting of the delivered rivet in the receiving holes of 30 the over-lapping work portions and subsequent heading of the inserted rivet shank. These steps constitute one complete cycle of operation of the machine.

The present machine incorporates various 35 devices which are mounted on a conventional machine frame 30, having a crankshaft 32 and a reciprocating ram 34 connected therewith. Drivably connectable with the crankshaft 32 through any conventional one revolution clutch (not shown) is a fly-wheel 36 which is driven by a 40 pinion (not shown) of an electric motor 38, mounted on a platform 40 of the machine frame 30. Any suitable friction brake 42 is permanently applied to the crankshaft 32 and may be adjusted by means of a clamping spindle 44. This brake prevents over-travel of the crankshaft after disengagement of the mentioned one revolution clutch which may be conveniently actuated by a foot pedal through a suitable connecting linkage (neither shown).

The various devices carried by the punch press frame 30 may be termed as follows: a work-holder A, a rivet delivering device B and a rivet setting and heading device C.

Workholder A

Referring particularly to Figs. 2 and 12, a bracket 50 is suitably mounted on the machine frame 30 and is provided with a recess 52 wherein a block 54 is locked by means of a set screw 56. This block is provided with a recess 58 in which a work support 60 is slidable. A plurality of compression springs 62 urges said work support into the position shown in Fig. 12 in which a retainer plate 64 on block 54 engages a flange 66 of said work support. Received in a recess 68 of block 54 and projecting into the work support 60 with a slide fit is a header 70 which also rests on a steel support 72 in block 54. Slidable in this header 70 is a pilot pin 76 which is normally urged with its frusto-conical surface 78 into engagement with a correspondingly shaped surface 80 of the header 70 by a compression spring 82. In the present instance two over-lapping work portions 84 to be riveted together are shown in the drawings. In Fig. 12, these work portions 84 are shown resting on the work support 60 with the pilot pin 76 projecting through the rivet receiving holes 86 of these over-lapping work portions. In this manner over-lapping work portions are properly located in the machine.

Rivet delivering device B

Referring more particularly to Figs. 1 to 7 inclusive, a frame 90 is mounted in any suitable manner on the machine frame 30 and provides a journal bearing 92 for a shaft 94 on which a hopper 96 is mounted. This hopper is generally cup-shaped and provided at its open end with a plurality of equi-angularly spaced, radial slots 98 which are just wide enough to let the shank 100 of a rivet 102 pass therethru. The open end of the hopper is so spaced from the plane wall 104 of frame 90 that a rivet head may comfortably pass therebetween. The hopper receives a supply of rivets, indicated by the dot-and-dash line in Fig. 4, through a suitable chute 106 and a corresponding opening 108 in the frame 90. A circular rib 110 of frame 90 extends in close proximity to well over half the circumference 112 of the hopper 96, and prevents the discharge from the hopper of rivets the heads and shanks of which are situated in the space between the frame wall 104 and the open end of the hopper and in the radial slots 98 of the latter, respectively, as best shown in Fig. 4. Another circular rib 114 of frame 90 extends concentrically of the hopper from the frame opening 108 to a rivet chute 116, but this rib 114 is considerably spaced from the hopper circumference 112. Mounted on top of rib 114 is an arcuate plate 118 the surface 120 of which is concentric of the hopper circumference 112 and is so spaced therefrom as to afford comfortable clearance for a rivet shank 100 but not for the rivet head. Hopper 96 is intermittently rotated clockwise as viewed in Fig. 4 in a manner to be described later, whereby the rivets therein are agitated and some of them will assume a position in which their shanks 100 enter some of the hopper slots 98. As best shown in Figs. 3 and 5, the inner wall of the open hopper end is curved outwardly so that the heads on those rivet shanks which project into hopper slots 98 may gravitate into the circular track 122 which is formed by the arcuate plate 118, the hopper periphery 112 and the frame wall 104 as best shown in Figs. 4 and 5. This track 122 is in direct communication at 124 with the rivet chute 116, a cross section of which is shown in Fig. 6.

Referring more particularly to Figs. 1 and 2, ram 34 is provided with a lug 130 through which extends a rod 132, linked at 134 to an arm 136, journaled on an extension 138 of a ratchet disc 140 which is mounted on the hopper shaft 94. This arm 136 carries a pawl 142 which is normally urged into engagement with the ratchet teeth 144. Interposed between the ram lug 130 and a collar 146 on rod 132 is a spring 148 which normally urges another collar 150 of rod 132 into engagement with said ram lug. Upon a downward stroke of the ram 34, rod 132 with its collars naturally follows the ram, resulting in idle riding of pawl 142 over some of the ratchet teeth 144. Upon the return stroke of the ram, spring 148 will be at first compressed and eventually forces rod 132 back into the position shown in Fig. 1, resulting in agitation of the hopper by means of the cooperating pawl 142 and ratchet teeth 144. Consequently, upon a return stroke of the ram 34, spring 148 is at first sufficiently compressed to overcome the considerable static friction in the hopper bearing so that at the start of the hopper the considerable, stored energy in said spring is almost suddenly released and accelerates the hopper to such an extent that the latter soon rotates faster than the pawl and comes to rest again considerably after the pawl stops. From all the foregoing it can be understood that the hopper is given enough impetus to accelerate the hopper sufficiently to considerably agitate the rivets therein, some of which will pass through the hopper slots 98 and into the arcuate track 122 and finally into the chute 116 as best illustrated in Fig. 4. Other rivets, though entering the hopper slots 98, cannot leave the same due to the adjacent arcuate rib 110. However, these latter rivets may finally descend into the arcuate track 122 on a subsequent agitation of the hopper as can be readily understood. In case a rivet shank should become jammed in a hopper slot as shown in Fig. 7, there is provided a member 160 which projects into the frame opening 108 and is provided with a camming surface 162 in close proximity to the hopper periphery 112. This surface 162 is adapted to engage the head of the jammed rivet and cam the same out of its slot, whereupon the released rivet will drop back into the hopper.

As best shown in Fig. 2, the rivet chute 116 terminates adjacent the rivet setting and heading device C. Alongside the rivet chute a mechanism is provided which is adapted to release one rivet at a time into the remaining chute. This mechanism will now be described with particular reference to Figs. 8 to 11 inclusive. Normally part of the chute 116 and communicating arcuate track 122 is filled with rivets the shanks of which extend in the same direction as follows from the foregoing description. Normally the shoulder 170 of a lever 172 engages the shank 100 of the lowermost rivet in the chute 116, thereby retaining the entire row or rivets in said chute and following arcuate track. This lever 172 is provided with an elongated slot 174 through which extends a pivot 176, secured to a bracket 178 on the machine frame 30. The chute 116 is also secured to this bracket 178 by a plurality of screws 180. Cooperating with lever 172 is another lever 182 having a substantially Z-shaped slot 184 through which extends a pivot 186, also secured to bracket 178. Both levers 172, 182 are connected at 188 with a link 190 which is pivotally mounted at 192 on bracket 178. One of the pivots 188 is longer and extends into a slot 194 of an arm 196 which is pivotally mounted at 198 to bracket 178.

as best shown in Fig. 11. Arm 196 carries near one of its ends a cam 200 which is substantially of diamond shape and may be adjusted longitudinally of said arm in a groove 202 thereof. 5 Adapted to cooperate with cam 200 is an anti-friction roller 204 which is carried by a holder 206, slideable in a groove 208 of a plate 210 which is vertically adjustably secured to ram 34 by means of bolts 212. Holder 206 is retained in its 10 guide groove 208 by a retainer plate 214 and is provided with a longitudinal bore 216, flanked by two diametrically opposite, longitudinal slots 218. Received in said bore 216 is a compression spring 220, one end of which bears against a pin 222 of holder 206 and the other end of which bears against a pin 224 which is secured to the plates 210, 214 and extends through the holder slots 218. A set screw 226 is adjustably secured to holder 206 and limits its movement to the left 15 as shown in Fig. 8. During a downward stroke of the ram from the uppermost position shown in Fig. 8, roller 204 engages the surface 228 of cam 200 and is thereby forced to the right against the compression of spring 220, since the cam carrying arm 196 is normally urged into engagement with another adjustable set screw 230 in bracket 178 by means of a tension spring 232 and consequently stopped against further 20 counterclockwise rotation as viewed in Fig. 8. 30 Roller 204 and holder 206 are even further moved toward the right as viewed in Fig. 8 when the former rides over surface 234 of cam 200. Consequently the cam carrying lever 196 remains stationary during the 35 entire work stroke of ram 34 and roller 204 is forced to dodge said cam. Immediately after roller 204 clears cam 200 during the work stroke of the ram, holder 206 is forced by the spring 220 to return into the position shown in Fig. 8. During the return stroke of the ram, roller 204 will engage the cam surface 236, causing arm 196 to rock clockwise as viewed in Fig. 8. Such rocking of arm 196 continues while the roller 204 cooperates with the cam surface 238 as follows from 40 Fig. 9 in which lever 172 is shown entirely retracted from the chute passage 117 and lever 182 is in the path of downward movement of the rivet shanks projecting from said passage 117. Immediately after roller 204 clears cam 200 during 45 further upward movement of the ram 34 from the position shown in Fig. 9, spring 232 forces the levers 172, 182 and arm 196 into the position of Fig. 8 as can be readily understood. While arm 196 is rocked clockwise from the position 50 shown in Fig. 8 to that shown in Fig. 9, in the just explained manner, the shank supporting shoulder 170 of lever 172 retracts from the chute passage 117 into the position shown in Fig. 9 and lever 182 simultaneously approaches said 55 chute passage until a shoulder 240 thereof is in the path of descent of the rivet shanks in the chute as shown in Fig. 9. Both levers 172, 182 are so coordinated that lever 182 is already in the path of descent of the lowermost rivet in the 60 chute when lever 172 is about to release said rivet, which then will descend upon the obstructing shoulder 240 of lever 182. Fig. 10 discloses the relative position of both levers 172, 182 just prior to the release of the lowermost rivet in the chute 65 by lever 172 and slight additional movement of lever 182 into obstructing position. Therefore, during a complete clockwise rocking of arm 196 from the position shown in Fig. 8 to that shown in Fig. 9, the entire row of rivets in the chute 70 75 will first descend upon shoulder 240 of lever

182 in which position the shank of the lowermost rivet is below the shoulder 170 of lever 172. The Z-shaped slot 184 of lever 182 results in slight upward movement of the shoulder 240 thereof while approaching the chute passage 117 to assure that the shoulder 170 of lever 172, when again returning from the position shown in Fig. 9 to that shown in Fig. 8, will actually move into the path of descent of shank 100a of the consecutive rivet and thus prevent that this rivet slips past said shoulder 170 and eventually past shoulder 240 of the half-withdrawn lever 182. Of course, as soon as roller 204 clears cam 200 during the return stroke of the ram, the levers 172, 182 return immediately from the position shown in Fig. 9 to that shown in Fig. 8, whereupon the lowermost rivet, which is then resting on shoulder 240 of lever 182 is released from lever 182 and free to pass through the remaining chute. 20

Rivet setting and heading device C

Referring more particularly to Figs. 12 to 20 inclusive, the bracket 50 provides guideways 250 for a slide 252 which is preferably provided with several cavities 254 to reduce its weight. Secured to slide 252 is a lug 256 which is adapted to cooperate with adjustable set screws 258 which determine the uppermost and lowermost position of said slide. The structure for moving the slide will be described later in a more opportune connection. Pivotally connected at 260 with slide 252 are four links 262 which are also pivotally connected at 264 with the two identical halves 266 of a rivet setting head 268. Two of these pivots 260 carry depending arms 270 to which a tension spring 272 is applied, normally urging the two halves 266 into the closed position shown in Fig. 13. Since this head 268 has been first formed and cylindrically bored as an integral piece and subsequently split in halves by sawing for instance, and since the cylindrical shape of complementary bores in both halves 266 has to be maintained for reasons which will appear obvious later, cam sleeves 274 are secured to those pivots 260 which carry the depending arms 270. As best shown in Figs. 13 and 15, these sleeves 274 are provided with camming surfaces 276 which engage the adjacent surfaces 278 of slide 252 and thus prevent approach between the halves 266 beyond that shown in Fig. 13. The head 268 is provided with a bore 280 which merges into a slightly smaller bore 282, terminating in a tapered recess 284. Bore 282 is of such diameter that a rivet head may readily slide therein and the tapered recess 284 terminates in a cylindrical mouth 286 which is of such diameter that a rivet shank may slidably fit therein. As best shown in Fig. 13, the head 268 is provided with a wide gate 288 which merges into a narrow gate 290. The bottom surface 292 of gate 288 is inclined and in the uppermost position of the head 268 as shown in Fig. 12 is so aligned with the rivet chute 116 that a rivet from the chute will pass through the gates 288, 290 and finally descend through the bores 280, 282 into the full line position shown in Fig. 12. In this manner a released rivet passes through the lower part of the rivet chute 116 and is received by the head 268. The upper set screw 258 in Fig. 12 is so adjusted that in the explained uppermost position of the head, the bottom surface 292 of gate 288 is flush with the chute surface 294 on which the head of a rivet slides while descending in the chute. 60

As best shown in Fig. 12, a sleeve 300 is secured to the slide 252. This sleeve slidably receives a 75

rod 302 having an enlarged head 304 against which bears one end of a compression spring 306 the other end of which bears against the sleeve 300. Rod 302 is connected at 308 to the ram 34.

5 Secured in any suitable manner to the ram 34 is a punch 310 which in the uppermost position of ram 34 and slide 252, i. e. in inoperative position of the machine, assumes the position shown in Fig. 12 in which there is enough clearance between said punch and the entrance gate 288 of the head 268 to permit free passage of a released rivet therein. Immediately after ram 34 starts on a work stroke, the slide 252 with the parts carried thereby starts to descend by gravity since the maximum compression of spring 306 in the compressed state shown in Fig. 12 is just sufficient securely to hold slide 252 in engagement with the upper set screw 258. The punch 310 catches the rivet in the slower descending head 268 substantially in the position of slide 252 as shown in Fig. 16. Since the gravity of the slide 252 assists in its descent, it follows that thereafter punch 310 and head 268 descend simultaneously until they arrive in the position shown in Fig. 17 in which slide 252 is stopped by the lower set screw 258. However, just before the head 268 arrives in its lowermost position, the rivet therein registers with the earlier mentioned pilot pin 76 which is provided with a tapered tip 312, projecting into a correspondingly shaped recess of the rivet shank. Upon continued descent of punch 310 from the position shown in Fig. 17 successively into the positions shown in Figs. 18 and 19, punch 310 which engages the rivet head with its concave surface 316 forces said rivet into the receiving holes 86 of the overlapping work portions 84 against the tendency of the compression spring 82 normally to urge the pilot pin 76 into the position shown in Fig. 12 or 17. It is obvious from Fig. 20 that the forced rivet spreads the two halves of head 268 apart against the tension of spring 272. When the rivet head engages the overlapping work portions 84 as shown in Fig. 18, the further descending punch 310 forces the work support 60 from the position shown in Fig. 18 to that shown in Fig. 19 against the compression of the springs 62. During such combined movement of the rivet, the work support and the punch, the rivet shank is headed over by the inwardly tapered or concave surface 318 of the header 70. Immediately after the ram 34 starts on its return stroke, work support 60 is returned into the position shown in Fig. 18 by the compression springs 320. During the return stroke of the ram, the spring 306 engages sleeve 300 and the same is gradually compressed until the compression thereof overcomes the weight of the slide 252 and the parts carried thereby, whereupon said slide follows the ram into the uppermost position shown in Fig. 12 in which the rivet chute is again in alignment with the entrance gate 288 of the head 268 at the time another rivet is released from the chute. At the very start of the ram 34 on its return stroke, the punch 310 withdraws from the spread halves of head 268 and the same are returned into the position shown in Fig. 13 before spring 306 reengages sleeve 300.

Mode of operation of machine

70 After the operator has brought the rivet receiving holes of overlapping work-portions into registry with the pilot pin 76, the operator starts the machine for one complete cycle of operation 75 by causing engagement of the earlier mentioned

one revolution clutch (not shown). During the following workstroke of the ram 34, the rivet which was received in the head at the end of the preceding cycle of operation of the machine is forced into the receiving holes of the overlapping work-portions and the projecting rivet shank is subsequently headed over in the earlier explained manner. During the return stroke of the ram 34, the hopper is agitated to effect an orderly discharge of rivets into the rivet chute, 10 and a single rivet is released from the chute which passes into the meanwhile returned head 268. This completes one cycle of operation of the machine. Thereafter, the operator places new work to be riveted in the machine in the earlier 15 explained manner and starts the machine for a new cycle of operation.

While the embodiment of the present invention as herein disclosed, constitutes a preferred form, it is to be understood that other forms might be adopted, all coming within the scope of the claims which follow.

I claim:

1. In a riveting machine, the combination of a rivet chute; a device for permitting passage of the foremost rivet in the chute only; means including a pivotally mounted lever for actuating said device upon rocking said lever into opposite end positions; a cam on the lever, said cam having opposite faces; a stop for the lever in one end position; means yieldingly urging the lever against said stop; a reciprocable element having a shoulder; a cam roller slidable on said element transversely of its direction of reciprocation; an adjustable stop on the roller to cooperate with said shoulder; and a spring urging the roller with its stop into engagement with said shoulder, one face of the cam cooperating with the roller to force the lever into engagement with its stop and to move the roller away from the shoulder during movement of the element in one direction, and the other face of the cam cooperating with the roller to force the roller with its adjustable stop against the shoulder and to rock the lever away from its stop during movement of the element in the opposite direction.

2. In a riveting machine, the combination of a rivet chute; two members movable transversely of the chute and having portions adapted to obstruct the advance of rivets in the chute and being so spaced from each other as to admit only one rivet therebetween; means including a pivotally mounted lever for simultaneously moving one member into obstructing position and withdrawing the other member from obstructing position and vice versa upon rocking said lever into opposite end positions; a cam on the lever, said cam having opposite faces; a stop for the lever in one end position; means yieldingly urging the lever against said stop; a reciprocable element having a shoulder; a cam roller slidable on said element transversely of its direction of reciprocation; an adjustable stop on the roller to cooperate with said shoulder; and a spring urging the roller with its stop into engagement with said shoulder, one face of the cam cooperating with the roller to force the lever into engagement with its stop and to move the roller away from the shoulder during movement of the element in one direction, and the other face of the cam cooperating with the roller to force the roller with its adjustable stop against the shoulder and to rock the lever away from its stop during movement of the element in the opposite direction.

3. In a riveting machine, the combination of a

5 rivet chute; a device for permitting passage of the foremost rivet in the chute only; mechanism receiving a rivet from the chute and holding said rivet in alignment with the registering apertures of work portions to be joined; a reciprocable ram for forcing a rivet from the mechanism and into said apertures, said ram having a shoulder; means including a pivotally mounted lever for actuating the device upon rocking said lever into 10 opposite end positions; a cam on the lever, said cam having opposite faces; a stop for the lever in one end position; means yieldingly urging the lever against said stop; a cam roller slidable on the ram transversely of its direction of reciprocation; an adjustable stop on the roller to cooperate with said shoulder; and a spring urging the roller with its stop into engagement with said shoulder, one face of the cam cooperating with the roller to force the lever into engagement with its stop and to move the roller away from the shoulder during movement of the ram in one direction, and the other face of the cam cooperating with the roller to force the roller with its adjustable stop against the shoulder and to rock the lever away from its stop during movement of the 20 ram in the opposite direction.

4. In a riveting machine, the combination of a rivet chute; two members movable transversely of the chute and having portions adapted to obstruct the advance of rivets in the chute and being so spaced from each other as to admit only one rivet therebetween; means including a pivotally mounted lever for simultaneously moving one member into obstructing position and withdrawing the other member from obstructing position and vice versa upon rocking said lever into opposite end positions; mechanism receiving a rivet

from the chute and holding said rivet in alignment with the registering apertures of work portions to be joined; a reciprocable ram for forcing a rivet from the mechanism and into said apertures, said ram having a shoulder; a cam on 5 the lever, said cam having opposite faces; a stop for the lever in one end position; means yieldingly urging the lever against said stop; a cam roller slidable on the ram transversely of its direction of reciprocation; an adjustable stop 10 on the roller to cooperate with said shoulder; and a spring urging the roller with its stop into engagement with said shoulder, one face of the cam cooperating with the roller to force the lever into engagement with its stop and to move the roller 15 away from the shoulder during movement of the ram in one direction, and the other face of the cam cooperating with the roller to force the roller with its adjustable stop against the shoulder and to rock the lever away from its stop 20 during movement of the ram in the opposite direction.

5. In a machine for heading rivet shanks having a conical recess in their bottoms, the combination of a support for work to be riveted; a yielding pin normally projecting through the rivet receiving aperture of the work, said pin having a conical tip adapted to register with the recess of a rivet shank to be inserted in the work and guide the same through the aperture of the 25 work; a heading tool including the conical pin tip, said tip being adapted to cause the shank metal to flow laterally into the head-forming cavity of the tool upon movement of the rivet shank toward the stopped pin; and means stopping the 30 pin in cooperative position with the tool.

EDWARD TURNQUIST.
